UNITED STATES PATENT OFFICE

JOHN GARVIN, OF WEST MERIDEN, CONNECTICUT.

IMPROVEMENT IN DIES FOR MAKING BODY-LOOPS FOR CARRIAGES.

Specification forming part of Letters Patent No. 173,854, dated February 15, 1876; application filed January 15, 1876.

To all whom it may concern:

Be it known that I, JOHN GARVIN, of West Meriden, in the county of New Haven and State of Connecticut, have invented a new and useful Improvement in making Body-Loops for Carriages, of which the following is a specification:

Figure 1 is a face view of the dies by which my improved body-loops are formed. Fig. 2 is a section of the same taken through the line $x\ x$, Fig. 1, the dies being put together. Fig. 3 is a detailed section of the same, taken through the line $y\ y$, Fig. 1, the dies being put together. Fig. 4 is a detailed side view of one of the body-loops.

Similar letters of reference indicate corresponding parts.

The object of this invention is to furnish an improved mode of making body-loops for carriages, enabling them to be formed quickly and accurately, and with the countersink to receive the square tapering head of the bolts by which they are secured to the spring-bars.

The invention consists in the two sets of dies, consisting of the forming-dies, made with recesses to form the lug, head, and prong, and the finishing-dies made with the recesses, and the projection to finish the loops, and form the countersink for the bolt-head, as hereinafter fully described.

A and B are the dies by which the form is given to the body-loop C. The dies A and B strike up the loop C, form its edges, and are

made with recesses $a^1\ b^1$ to form the lug c^1 , with recesses $a^2\ b^2$ to form the head c^2 , and with recesses $a^3\ b^3$ to form the prong c^3 . The burrs formed upon the upper and lower sides of the loop C are then trimmed off, and the loops C are struck up in the dies D E, from their upper and lower sides, to finish them, and to form the square tapering countersink in the head c^2 . The die D is formed with a recess, d^1 , to receive the lug c^1 , and the die E is formed with recesses e^1 and e^2 , to receive the head c^2 and the prong c^3 . In the bottom of the recess e^1 is formed a projection, e^3 , to form the countersink in the head c^2 . The two dies A B and D E may be formed in the same pair of blocks, as shown in Fig. 1, or they may be formed in separate pairs of blocks, as may be desired.

Having thus described my invention, I claim as new and desire to secure by Letters Patent—

Jointly the two sets of dies, consisting of the forming-dies A B, made with recesses $a^1\ a^2\ a^3\ b^1\ b^2\ b^3$, to form the lug head and prong, and the finishing-dies D E, made with the recesses $d^1\ e^1\ e^2$, and the projection e^3 , to finish the loops, and form the countersink for the bolt-head, substantially as herein shown and described.

JOHN GARVIN.
